(57) **CLAIM**

The ornamental design for a USB docking station, as shown and described.

DESCRIPTION

FIG. 1 is a first perspective view of a USB docking station showing my design;

FIG. 2 is a second perspective view thereof;

FIG. 3 is a third perspective view thereof;

FIG. 4 is a front view thereof;

FIG. 5 is a back view thereof;

FIG. 6 is a left side view thereof;

FIG. 7 is a right side view thereof;

FIG. 8 is a top view thereof;

FIG. 9 is a bottom view thereof;

FIG. 10 is a perspective view of another state of the USB docking station thereof; and,

FIG. 11 is an enlarged view of the selected portion in FIG. 2.

The broken lines shown in the drawings depict portions of the USB docking station in which the design is embodied that form no part of the claimed design.
